(57) **CLAIM**

I claim the ornamental design for a soft spout, as shown.

DESCRIPTION

FIG. 1 is a perspective view of a first embodiment of a soft spout for a drinking container;

FIG. 2 is a front elevation view of the soft spout according to the present invention;

FIG. 3 is a right side elevation view of the soft spout according to the present invention;

FIG. 4 is a rear elevation view of the soft spout according to the present invention;

FIG. 5 is a left side elevation view of the soft spout according to the present invention;

FIG. 6 is a bottom planar view of the soft spout according to the present invention;

FIG. 7 is a top planar view of the soft spout according to the present invention;

FIG. 8 is a right side cross-section elevation view of the soft spout of the first embodiment according to the present invention; and,

FIG. 9 is a front cross-section elevation view of the soft spout according to the present invention.

The broken lines illustrate portions of the spout which form no part of the claimed design.
